UNITED STATES PATENT OFFICE.

MYER H. LEBOLT, OF CHICAGO, ILLINOIS, ASSIGNOR TO LEBOLT & COMPANY, OF CHICAGO, ILLINOIS, A CORPORATION OF ILLINOIS.

DESIGN FOR A WEDDING-RING.

57,681.

Specification for Design.

Patented Apr. 26, 1921.

Application filed November 26, 1920. Serial No. 426,653. Term of patent 14 years.

To all whom it may concern:

Be it known that I, MYER H. LEBOLT, a citizen of the United States, residing at Chicago, in the county of Cook, State of Illinois, have invented a new, original, and ornamental Design for Wedding-Rings, of which the following is a description, reference being had to the accompanying drawing, forming a part thereof.

The figure is a perspective view of a wedding ring, embodying my new design.

I claim:

The ornamental design for a wedding ring, as shown.

In testimony whereof, I affix my signature, in the presence of two witnesses.

MYER H. LEBOLT.

Witnesses:

ROSE K. CHIMBEROFF,
ARABELLA CHERRINGTON.
